(57) CLAIM

The ornamental design for a bag holder, as shown and described.

DESCRIPTION

FIG. 1 is a diagrammatic perspective view of the bag holder showing my new design;

FIG. 2 is a front elevational view thereof, the rear elevational view being a mirror image of the front view thereof;

FIG. 3 is a top plan view thereof;

FIG. 4 is a bottom plan view thereof;

FIG. 5 is a left side elevational view thereof; and,

FIG. 6 is a right side elevational view thereof.

The broken line showing of the bag in FIG. 1 is for illustrative purposes only and forms no part of the claimed design.
